US00D855636S

(12) **United States Design Patent** (10) **Patent No.:** **US D855,636 S**
Hu (45) **Date of Patent:** **** Aug. 6, 2019**

(54) **MOBILE PHONE WITH GRAPHICAL USER INTERFACE**

(71) Applicant: **BEIJING SOGOU TECHNOLOGY DEVELOPMENT CO., LTD.**, Beijing (CN)

(72) Inventor: **Miaoli Hu**, Beijing (CN)

(73) Assignee: **BEIJING SOGOU TECHNOLOGY DEVELOPMENT CO., LTD.**, Beijing (CN)

(**) Term: **15 Years**

(21) Appl. No.: **29/595,912**

(22) Filed: **Mar. 3, 2017**

(30) **Foreign Application Priority Data**

Sep. 29, 2016 (CN) 2016 3 0489422

(51) **LOC (12) Cl.** **14-04**

(52) **U.S. Cl.**

USPC **D14/486**

(57) **CLAIM**

The ornamental design for a mobile phone with graphical user interface, as shown and described.

DESCRIPTION

FIG. 1 is a front view of a first embodiment of a mobile phone with graphical user interface, showing my new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof; and,

FIG. 6 is a front view of a sixth embodiment thereof. The cellphone shown in broken lines depict environmental where a graphical user interface is embodied that forms no part of the claimed design.

1 Claim, 6 Drawing Sheets
